UNITED STATES PATENT OFFICE.

WILLIAM HOY BRADLEY, OF SPRINGFIELD, OHIO, ASSIGNOR TO THE AUTOMATIC METAL PRODUCTS COMPANY, OF SPRINGFIELD, OHIO, A CORPORATION OF OHIO.

METAL-WORKING MACHINE.

1,390,978.

Specification of Letters Patent. Patented Sept. 20, 1921.

Application filed January 2, 1920. Serial No. 348,887.

To all whom it may concern:

Be it known that I, WILLIAM HOY BRADLEY, citizen of the United States, residing at Springfield, in the county of Clark and 5 State of Ohio, have invented certain new and useful Improvements in Metal-Working Machines, of which the following is a specification.

This invention relates to improvements in 10 metal working machines, it more particularly relating to a machine of an automatic character for forming nut blanks from bars of stock.

One of the objects of the invention is to 15 provide a machine of this character equipped with a plurality of nut blank forming and stock feeding devices so that a plurality of blanks may be simultaneously formed at a single operation.

20 A further object of the invention is to provide improved gripping devices for the stock during the drilling and severing operations and for releasing said gripping devices during the feeding operation of the 25 stock.

A further object of the invention is to provide improved cutting mechanism for severing the blanks from the bars of stock.

20 A further object of the invention is to 30 provide feeding devices of an improved character for automatically feeding the stock after the completion of the nut blank.

35 A further object of my invention is to provide means for preventing the operation of the feeding devices until after the severing tools have completed their operation and been withdrawn from operative position.

40 A further object of my invention is to 45 simplify the construction and make more effective the operation of machines of this character.

Further objects of the invention will appear from the accompanying drawings and 45 specification.

In the drawings:

Figure 1 is a side elevation of the front of a machine embodying the improvements.

Fig. 2 is a top plan of the same.

50 Fig. 3 is a partial transverse section of some of the operating devices for the feeding mechanism, looking at the same from the rear side of the machine.

Fig. 4 is a detail of the same.

55 Fig. 5 is a detail of the same.

Fig. 6 is a vertical section on the line 6—6 of Fig. 1, with the drills and some of the other parts omitted.

Fig. 7 is a view of the front end of the machine.

60 Fig. 8 is a rear side view of a portion of the machine.

Fig. 9 is a section on the line 9—9 of Fig. 3.

Fig. 10 is a section on the line 10—10 65 of Fig. 3.

Fig. 11 is a section on the line 11—11 of Fig. 9.

Fig. 12 is a longitudinal section of one of the stock holding spindles and some of the parts associated therewith.

Fig. 13 is a plan view of a portion of the same.

Fig. 14 is an end view of the same.

Fig. 15 is an end view of the spindle col- 75 lars.

Fig. 16 is a side view of the same.

Fig. 17 is an end view of one of the dog collars.

Fig. 18 is a side view of the same.

Fig. 19 is a side of the stock feed finger.

Fig. 20 is an end view of the same.

Fig. 21 is a longitudinal section of one of the drill spindles and parts associated therewith, the figure being a continuation of 85 Fig. 12.

Figs. 22 to 27 inclusive are details of the drill spindle locking device.

Fig. 28 is a vertical section through the stock mandrels, and gripping and feeding 90 devices therefor, the section being on the line 28—28 of Fig. 2 with some of the parts omitted.

Fig. 29 is a detail of some of the operating devices for the drills.

95 Referring to the drawings, 1 represents a supporting frame resting upon legs 2, 3 is a head stationarily mounted on the frame, and 4 is another head slidably mounted on the frame. This frame and the two heads 100 serve to support and house all of the operating parts. Power is applied to the different mechanisms through a main drive shaft 5 and its pulley 6, this shaft being geared to the stock carrying mandrels and the drills 105 in the manner to be described, and also has a connection to a cam shaft 7 through a pinion 8 and gear 9, inclosed in a housing H (shown in dotted lines in Fig. 1) and change of speed gearing (not shown) be- 110

tween the said pinion and gear. A plurality of stock gripping, rotating and feeding devices are employed, as well as a plurality of drills and cutters for the stock, four sets 5 of these devices being shown in the present machine.

Stock gripping and rotating devices.

Inasmuch as all sets of these devices are 10 constructed exactly alike, but one of them will be described in detail, reference being had more particularly to Figs. 1, 2, 12, 13, 14, 15, 16, 17 and 18. These devices are mounted in the stationary head 3 in uniform 15 manner about the drive shaft 5, which is rotatably mounted, not only in the heads 3 and 4, but in bearings on the supporting bed 1. Referring to Fig. 12, 10 represents a mandrel having an outwardly flared or conical- 20 shaped inner end 10^a, the mandrel being journaled in bushings 11 and 12 in the bearings 13 and 14 of the head 3. Slidably mounted in the mandrel 10 is a sleeve 15 having secured to its inner end by a threaded 25 connection a split sleeve portion 16 having a conical-shaped outer surface to conform to the conical shape of the inner end 10^a of the mandrel. The conical-shaped portion of this 30 split sleeve is provided with a series of col- 35 lets 17 of a shape to conform to the stock, which in the present case is of hexagonal form and is represented by S. Secured to the outer end of the mandrel is a collar 18 (Figs. 15 and 16 for detail). Slidably 40 mounted upon the sleeve 15, but keyed thereto, is another collar 19 (Figs. 17 and 45 18 for detail). Slidably mounted upon the mandrel is a third collar 20 having an ex- 50 tended cone-shaped surface 21. As shown in Figs. 17 and 18, the collar 19 has two 55 projecting lugs 19^a and to these lugs are piv- 60 otted by pins 22 a pair of dogs 23. As shown in Figs. 15 and 16, the collar 18 has for- 65 wardly extending projections 18^a, and these 70 projections lie in the same plane as the noses 23^a of the dogs; the tails 23^b of the dogs lying in the path of the cone-shaped surface 21. Two nuts 24 and 25, one a lock for the 75 other, are threaded upon the outer end of 80 the sleeve 15. The collar 20 is peripherally 85 grooved to receive a ring 26. Rotatably mounted in suitable bearings at each side of the machine are vertically-arranged spindles 28. (See Fig. 28 for detail.) Each 90 95 spindle has a pair of arms 29, with forked ends to fit the pins 27^a of a pair of double yokes 27 which are loosely connected to the respective rings 26 by pins 27^b one pin being threaded into each side of each yoke mem- 100 ber. Each spindle also has an arm 30, the arms being provided with intermeshing gear segments 30^a. One of the arms 30 is pro- 105 vided with a cam roller 31 which is located in a camway of a cam 32 secured to a shaft 110 115 33. This shaft 33 is arranged in line with

the shaft 7 and mechanism hereinafter to be described is provided for throwing the shaft 33 into driving relation with the shaft 7 during one complete revolution of the latter. On each of the projections 18^a of the collar 18 is a laterally-extending ear 18^b provided 70 with a perforation 18^c and on the collar 19 is a pair of oppositely-arranged ears 19^b provided with threaded openings 19^c and with recesses 19^d. In the assembled condition of the parts the ears 18^b lie in the recesses 19^c, as indicated in dotted lines in Fig. 13. Extending through the perforations 18^c of the ears 18^b and threaded into the openings 19^c of the ears 19^d are rods 34. Inter- 80 posed between the ears 18^b and nuts 35 on these rods are coil springs 36, these springs 36 tending to cause the collar 19 to approach the collar 18.

In operation, assuming the parts to be in 85 tightened position as shown in Fig. 12, the first movement of the cam 32 slides the collar 20 rearwardly and releases the dogs 23 from the cam surface 21. The dogs are then free to swing upon the pins 22 and the 90 springs 36 will draw the collar 19 rearwardly from the nut 25, causing the collets to release the stock after which the cone 21 will be moved forwardly causing the beveled portion thereof to swing the tails of 95 the dogs outwardly. The noses 23^a of the dogs, contacting the projections 18^a of the collar 18, will force the collar 19, and, through the nut 25, likewise the collet sleeve 15, forwardly and thus tighten the collets 100 upon the stock.

The mandrel 10 is rotated from the drive shaft 5 through the gear 37 suitably connected to the mandrel and pinion 38 on the shaft 5. Nuts 39 and 40, one a lock for the 105 other, serve to hold the gear 37 in position. To take up end thrust on the mandrel, there are provided two thrust collars 41 and 42 with interposed anti-friction balls 43 loosely mounted on a bushing on the mandrel and 110 held in position by the nuts 44 and 45, one being a lock for the other.

By the arrangement described, the gripping tubes, due to the action of the springs, will be caused to readily release the bars of 115 stock when the dogs are free from the cones; further, in tightening the collets upon the work, the frictional engagement of the cones with the dogs is such as to facilitate the gripping action by tending to force the dog 120 sleeve forwardly against the nuts 24 and 25; and, further, by the arrangement of the sliding dog collars and the nuts 24 and 25, which act as abutments therefor, a strong connection between the dogs and gripping 125 tubes is had.

Stock feeding devices, (Figs. 1, 2, 7 and 12.)

During the interval between the releasing and the locking of the collets 17 upon the 130

stock, the stock is fed rearwardly to place a new portion thereof in operative relation with the drilling and cutting tools. Slidably mounted in the collet tube 15 is a feed tube 46. The rear end of the feed tube has secured thereto by a threaded connection an auxiliary split tube portion or feed finger 47 of resilient metal having its extreme inner end shaped to conform to the contour of the stock. Threaded to the other end of the tube 46 is a collar 48 grooved to receive a ring 49. Slidably mounted on a rod 50 secured to the head 3 and projecting forwardly therefrom is a hub or sleeve 51 provided with a plurality of yoke-shaped extensions 52, one for each feed tube. The bifurcated portion of each of these extensions embraces a ring 49 and have studs 53 threaded therein which project loosely into recesses in the rings. The hub 51 has a groove 54 (Fig. 12) within which extend pins on the yoke-shaped upper end of an arm 55 (Figs. 1 and 7) on a rock-shaft 55^a. The rock-shaft has at one end thereof a downwardly extending arm 55^b having pivotally connected therewith a link 56, the other end of which has an adjustable connection through a bolt 57 with a slotted curved arm 59 secured to a rock shaft 60 rotatably mounted in the bed frame 1. Also secured to the rock shaft is another arm 61 having a cam roll 62 which operates in the cam groove of the cam 32. So soon as the collets 17 have been released from the stock in the manner heretofore described the cam groove of the cam 32 will through the connections described, slide the sleeve 51 and hence all the feed tubes 46 so as to feed all of the bars of stock rearwardly by reason of the impingement of the flexible feed finger 40 or tube section 47 upon the stock, further movement of the cam returning the feed tubes to their normal position.

In order to insure feeding the bars of stock a uniform distance at each feeding operation, there are provided a plurality of stops 170 (Figs. 1, 2, 6 and 21), one for each bar of stock. Each of these stops 170 is adjustably secured by the headed screw 171 to an arm 172 on a sleeve 173; the arm having a slotted opening 172^a to provide for the adjustment. The sleeve 173 is split and is mounted upon a stud 174 projecting from the head 3, the sleeve having ears 175 to receive a bolt 176 by which it is clamped to the stud, and a nut 177 threaded on a reduced end portion of the stud provides for securing the proper longitudinal adjustment of the sleeve. The lower end of the stop is formed with a notch, 170^a as shown in Fig. 6, to accommodate the adjacent drill. The stops will be set for the proper thickness of the nuts and the adjustment of the devices which operate the feed tubes will be such as to insure the stock being fed against the stops, any additional movement of the feed

tubes being compensated for by the slippage of the tube fingers upon the stock.

By the arrangement of feed described, the feed tubes are not only withdrawn but moved in the feeding direction in a positive manner, and, further, by the construction of feed fingers, in connection with the stops, the stock is insured a definite length of feed upon each operation of the devices, requiring no fine adjustment of the feeding devices themselves, the stops determining the amount of feed and the feeding devices being allowed an additional movement if necessary by reason of the permitted slippage of the feed fingers upon the stock. 80

In order to prevent overthrow of the cam 32, the shaft 33 is provided with a brake drum 63 and band 64 which is adjusted so as to exert sufficient friction to bring the parts at rest as soon as the shaft 33 is disconnected from the shaft 7 in the manner hereinafter explained. 85

Stock drilling devices.

In the present machine there is provided four drills, one of which is shown in detail in Fig. 21. All of these drills are carried by the head 4, which slides in ways on the bed frame so as to cause the drills to be gradually fed into the stock and withdrawn therefrom. The head is reciprocated in the following manner, (Figs. 1, 2 and 29): An arm 65 is connected to a rock-shaft 66, provided with an arm 66^a with its upper end connected to the head 4 by the links 67. The lower end of the arm 65 is provided with a slot 68 in which is secured an adjustable wrist pin 69, which extends into a slotted opening in an arm 69^a on a shaft 69^b, which has an arm 69^c, provided with a cam roller 69^d which cooperates with the cam 71 to reciprocate the arm; the cam being so formed that the drills will be gradually fed into the stock but quickly withdrawn therefrom by the action of a spring 69' connected to the arm 69'' on the shaft 69^b when the drilling operation is completed. The cam is rotated (see Fig. 1) at a slow speed from the shaft 7 through the medium of the pinion 72, fast on the shaft 7, gear 73 secured to the sleeve 74 loose on a counter-shaft 75, gear 76 integral with the sleeve 74, gear 77 connected with sleeve 78 loose on the shaft 7, pinion 79 connected with the sleeve 78, gear 80 secured to the shaft 75, pinion 81 secured to the shaft 75, and gear 82, having connected therewith the cam 71. 110

Referring now to Fig. 21, 83 represents the drill spindle having a tapered forward end, the tapered end of the spindle being mounted in the tapered bushing 84 and the rear end of the spindle in a bushing 85 in bearings formed in the head 4. The spindle is driven from the main shaft 5 through the medium of a gear 86 on said shaft, inter- 130

mediate gear 87, and gear 88 on the spindle; the intermediate gear 87 shown being one of two intermediate gears which transmit the motion from the drive shaft to all four of the spindles. The gear 88 is splined to the spindle and held in position by the nuts 89 threaded on the spindle, one being a lock for the other. End thrust upon the spindle is taken up by the end of the rear bearing, 10 through the thrust collars 90 having interposed anti-friction balls 91, the thrust collars and balls being held in position by the nuts 92, one of which is a lock for the other. Located in the spindle and splined thereto 15 is the holder 93 for the drill 94; the forward end of the spindle having a guide or support 95 for the drill.

Provision is made for adjusting the drill holder in the spindle. Threaded on the rear 20 end of the spindle is a housing 96 (Figs. 26 and 27) having an oblong rear opening 97. Threaded in the tool holder 93 is a screw 98 having a plain cylindrical portion 99 and an integral collar 100, as well as a threaded rear end portion 101. 102 (Figs. 22 and 23) represents an oblong shaped collar of a size which will permit it to enter the oblong opening 97 of the housing 96, and also having a forwardly-extending cylindrical boss 103 which enters the end of the spindle. 104 (Figs. 24 and 25) is a circular collar having an oblong boss 104^a corresponding to the oblong opening 97 of the collar 96. The collar 102 is provided with 30 a small opening 105 and the collar 104 with a projecting pin 106. In assembling the parts, the housing 96 is threaded on the end of the spindle and the collars 102 and 104 placed upon the cylindrical portion 99 of 35 the screw before the tool holder and drill have been inserted. When the tool holder is inserted in the mandrel the collar 102 is caused to register with the oblong opening 109 so as to enter the housing, after which 40 it may be given a quarter turn by means of the collar 104 and its pin 106 which has been inserted in the opening 105. The projecting boss 104^a of the collar 104 is then pushed into the oblong opening 97 and a 45 nut 107 threaded on the threads 101 is turned tightly against the collar 104 to hold the parts firmly clamped together.

By this construction, the drill and its holder may be quickly and readily removed 50 by simply unloosening the nut 107, withdrawing the boss 105 from the opening 97 and then giving the collar 102 a quarter turn to cause it to register with the opening 97.

60 *Stock severing devices, (Figs. 1, 2, 6, 12 and 21.)*

Journalized upon the shaft 5 is a sleeve 110 (Figs. 12 and 21), one end of which 65 extends into a bearing in the frame 1.

This sleeve has an integrally-formed cone 111 and a removable cone 112 held in position by the nuts 113. Clamped between the cones is the hub 114 of a tool carrier, the hub having four radially-extending 70 arms 115 to which are clamped the cutting tools 116. The holder also has an arm 117 which is pivotally-connected by an adjustable link 118 with a crank arm 120, secured to a rock shaft 121. The rock shaft 121 extends rearwardly and has a crank arm 122 pivotally-connected to one end of a cam lever 123, the other end of the cam lever being pivotally-connected to one arm of a bell crank lever 124, pivoted at 125 and 80 having pivotally-connected to its other arm, by a pivoted support 126^a, weights 126. The cam lever 123 carries a cam roller 127 which cooperates with a cam 128 connected with a sleeve 128^b which sleeve is connected 85 with and receives its motion from the cam 71 (Fig. 3), as a result of which the tools will be gradually fed into the stock and then when the roller 127 rides off of the high part of the cam and drops into the depression 128^a it will be quickly withdrawn so as to clear the tools from the path of the bars of stock as they are fed in the manner before described.

90 *Devices for preventing feed of stock until 95 after withdrawal of cutting tools.*

The parts are so timed that the operation of drilling and the withdrawal of the drills from the stock has been completed before 100 the completion of the cutting operation. In order to insure the complete withdrawal of the cutting tools prior to the beginning of the feeding operation, there is provided means for throwing the shaft 33, which 105 carries the stock feeding cam, into operative relation with the shaft 7 through the medium of the devices which operate the tools, as follows: Referring particularly to Figs. 3, 5, 9, 10 and 11, splined to the shaft 110 7 is one member 129 of a clutch, having ratchet teeth 130 on its outer periphery. Also splined to the shaft 33 is a second clutch member 131 having a housing 132 which overhangs the ratchet teeth 130 and 115 is preferably closed by a cover 133. The housing 132 is cut away as indicated at 134 and in this cut-away portion and pivotally-connected to the housing is a pawl 135 normally spring-pressed toward engaging position with the ratchet teeth by a flat spring 136. Extending laterally from the pawl 135 and through an opening 137 in the housing is a finger 138. This finger is normally held out of engagement with the 120 ratchet-teeth by the high part of a cam 139, slidably mounted upon the hub of the clutch member 131. Secured to the hub of the cam by set-screws 140 is a ring 141 having projecting pins 142 which extend loosely into 130

the arms of a two-part yoke 143 pivoted as at 144 to a bracket 145. The yoke has projecting arms 146 which are pivotally-connected to a rod 147, the other end of which is pivoted to an arm 148 of a bell crank lever, 150 representing the other arm thereof, pivoted on the pin 149^a carried by the bracket 149 (see Figs. 3 and 5). A coil spring 151 is placed about the rod 147 and 10 interposed between a projection 152 on the frame of the machine and a collar 153 on the rod. Pivotally-connected to a bracket 154 on the bifurcated lever 123 is a latch in the form of a bell crank lever, 155 and 156 representing the respective arms thereof; the arm 156 having a shoulder 157 formed by an extended face portion 158 at the extreme end thereof. Carried by the bifurcated lever 123 is a 20 pin 159 normally spring-pressed by a coil spring 160 into engagement with the arm 156 of the latch. An adjustable screw 161 in an extension of the frame forms a stop for the latch. The operation is as 25 follows:—

Assuming the clutch members to be in the position shown in Figs. 3 and 11, the cam 139 is holding the pawl 135 out of engagement with the clutch member 129 and the 30 cam roller 127 on the lever 123 is about to drop into the recess 128^a as shown in Fig. 6. When the cam roll drops into the recess the lever 123 will be given a rapid movement to the right which, by reason of the engagement of the arm 150 with the shoulder of the latch will rock the bell crank lever and cause the rod 147 to withdraw the cam 139 from beneath the finger 138, thus permitting the pawl to engage the clutch 35 member 129 so as to impart rotary movement to the shaft 33 and hence cause the cam to operate the feeding devices. Continued movement of the lever 123 will cause the arm 156 of the latch to engage the stop 40 161 and thus release the arm 150 from the latch, whereupon the spring 151 will throw the cam 139 back into the path of the finger 138, this being permitted because of the fact 45 that the low portion of the cam is now coinciding with the finger. The finger, riding upon the high portion of the cam will disengage the pawl from the ratchet wheel 129 so that the movement of the shaft 33 will be arrested. The cam 128 is now moving the 50 arm 123 and its latch to the left in Fig. 6, the end of the finger 150 will ride over the face 158 of the trip, and the trip under action of the spring 160, will again swing back to the position shown in Fig. 3 so 55 that upon the return movement of the lever 123 to the right it will again engage the arm 150 and operate it in the manner before described.

While there has been shown and described a machine which is especially adapted for

the forming of nut blanks, yet some of the constructions are equally applicable to other forms of metal working machines and I do not desire, therefore, to be limited to a machine of the exact character described. 70

Having thus described my invention, I claim:—

1. In a machine of the character described, a plurality of feeding devices for a plurality of bars of stock, one set of feeding devices 75 being associated with each bar of stock, a plurality of tools, one set being associated with each bar of stock, a main operating shaft centrally located with reference to the tools, an auxiliary supporting shaft similarly located with reference to the feeding devices, the said shafts being substantially in alinement, and an actuating device common to all of said feeding devices, said actuating device being operated by the main operating shaft and being supported upon said auxiliary shaft. 80

2. In a machine of the character described, a plurality of feeding devices for a plurality of bars of stock, a plurality of tools 90 for said bars of stock, a sliding head for supporting said tools, an auxiliary supporting shaft for the feeding devices and a main operating shaft, the last two-mentioned shafts being centrally located in relation to 95 the tools and feeding devices, a main cam shaft below the main operating shaft, and an auxiliary cam shaft intermittently operated by the main cam shaft, one cam shaft being connected to the feeding devices and 100 the other to the tools, for the purpose specified.

3. In a machine of the character described, stock feeding devices, forming devices for said stock, mechanism for positively feeding 105 the forming devices into the stock, weighted connections for withdrawing said forming devices, continuously operated driving devices, and means operated by said weighted connections for throwing said driving devices 110 into operative relation with said stock feeding devices.

4. In a machine of the character described, stock feeding devices, forming devices for said stock, mechanism for positively feeding 115 the forming devices into the stock, weighted connections for withdrawing said forming devices, continuously operated driving devices, means operated by said weighted connections for throwing said driving devices 120 into operative relation with said stock feeding devices, and means for disconnecting said operating devices from said stock feeding devices after a predetermined movement of the latter. 125

5. In a machine of the character described, stock feeding devices, stock cutting devices, a cam for operating said cutting devices, an operating device controlled by said cam together with connections for withdrawing 130

said cutting devices from the stock, and mechanism controlled by said operating device for operating said stock feeding devices.

6. In a machine of the character described, 5 stock feeding devices, cutting devices for said stock, a cam for feeding said cutting devices into the stock, an operating device controlled by said cam together with connections for withdrawing said cutting devices from the stock, a continuously operating shaft, and mechanism controlled by said operating devices connections for throwing said shaft into operative relation with said stock feeding devices, together with means 10 for disconnecting the same therefrom after a predetermined movement of said feeding devices.

7. In a machine of the character described, stock feeding devices including a driven 20 shaft, stock cutting devices, a cam for feeding said cutting devices into the stock, an operating device controlled by said cam together with connections for withdrawing said cutting devices from the stock, a continuously operating driving shaft, and mechanism including a clutch controlled by said operating device for throwing said shafts in driving relation with each other, together 25 with means for disconnecting the same after a predetermined movement of said driven shaft.

8. In a machine of the character described, stock feeding devices including a driven shaft, stock forming devices, mechanism for feeding said forming devices into the stock 35 and withdrawing the same therefrom, a driving shaft, clutch members on the respective shafts including a pawl and ratchet wheel, a cam for normally holding the pawl 40 out of engagement with said ratchet wheel, and devices operated by the withdrawing mechanism for said forming devices for causing said cam to release said pawl and engage said ratchet wheel, and a spring for 45 returning said cam to operative position relative to said pawl.

9. In a machine of the character described, a plurality of feeding devices for a plurality of bars of stock, a plurality of tools, each 50 tool being arranged to register with a bar of stock, a main operating shaft and a supporting shaft substantially centrally located with reference to the tools and feeding devices, a main cam shaft, an auxiliary cam 55 shaft intermittently operated by the main cam shaft, an actuator for the feeding devices supported by said supporting shaft, connections between the auxiliary cam shaft for operating said actuator, and means connecting the tools to the main operating shaft, 60 for the purpose specified.

10. In a machine of the character described, a plurality of feeding devices for a plurality of bars of stock, a sliding head, 65 a plurality of tools supported by said head,

a main operating shaft centrally located in its relation to said tools, means connecting same with said tools, an auxiliary supporting shaft in substantial alignment with the main operating shaft, a main cam shaft below the operating shaft, an actuator common to all said feeding devices on said supporting shaft, an auxiliary cam shaft located below said supporting shaft, means connecting the main operating shaft with 75 said cam shaft, and means connecting the actuator with said cam shaft, for the purpose specified.

11. In a machine of the character described, a plurality of stock holding devices, 80 a movable severing tool support common to all of said devices, severing tools carried by said support, one associated with each of said holding devices, and mechanism for positively rocking said tool support to feed 85 said tools simultaneously into the stock, together with means for withdrawing the same therefrom.

12. In a machine of the character described, a plurality of stock holding devices, 90 an oscillatory tool support common to all of said devices, a plurality of tools mounted upon said support, one of said tools associated with one of said holding devices, a cam for oscillating said support in one direction to simultaneously feed all of said tools into the stock, and means for oscillating said support in the opposite direction to simultaneously withdraw all of said tools from the stock.

13. In a machine of the character described, a support, a spindle revolubly mounted in said support, a tool holder removably carried by said spindle, a housing fixed to the end of said spindle having an 105 oblong opening, a collar loosely connected with said tool holder of an oblong shape conforming to said oblong opening, a second collar loosely connected with said tool holder having a loose rotatable connection with said 110 oblong collar so as to turn the same relatively to said housing to form an interlocking connection, and means for locking said second mentioned collar.

14. In a device of the character described, 115 a support, a spindle rotatably mounted in said support, a tool holder removably mounted in said spindle but rotatable therewith, a tool carried by said holder, an adjusting screw threaded in said holder, 120 a housing connected with the end of said spindle having an oblong opening, a collar loosely mounted on said screw of an oblong shape to enter said opening, a fixed collar on said screw adjacent said oblong collar, 125 and means for turning said oblong collar in said opening to form an interlocking connection between said collar and housing.

15. In a machine of the character described, 130 a support, a spindle rotatably

mounted in said support, a tool holder removably mounted in said spindle but rotatable therewith, a housing fixed to the end of said spindle provided with an oblong opening, a collar of an oblong form to enter said opening, means for turning said collar in said housing to form an interlocking connection between the two, and an abutment

between said tool holder and said oblong collar.

In testimony whereof I have hereunto set my hand this 18th day of December, 1919.

WILLIAM HOY BRADLEY.

Witness:

CHAS. I. WELCH.
